UNITED STATES PATENT OFFICE.

ISAAC T. SMITH, OF ROCKY MOUNT, NORTH CAROLINA.

DESIGN FOR THE BACK OF PLAYING CARDS.

61,352.

Specification for Design.

Patented Aug. 8, 1922.

Application filed December 9, 1921. Serial No. 521,262. Term of patent 14 years.

To all whom it may concern:

Be it known that I, ISAAC T. SMITH, a citizen of the United States, residing at Rocky Mount, in the county of Nash and State of North Carolina, have invented a new, original, and ornamental Design for the Backs of Playing Cards, of which the following is a specification, reference being

had to the accompanying drawing, forming part thereof.

The figure is a face view of the back of a playing card showing my new design.

I claim:

The ornamental design for the backs of playing cards, as shown.

ISAAC T. SMITH.
